[57] CLAIM

The ornamental design for a fireplace bumper pad, as shown and described.

DESCRIPTION

FIG. 1 is a front elevational view of fireplace bumper pad showing my new design;

FIG. 2 is a rear elevational view thereof;

FIG. 3 is a right side elevational view thereof, on an enlarged scale;

FIG. 4 is a left side elevational view thereof, on an enlarged scale;

FIG. 5 is a top plan view thereof;

FIG. 6 is a bottom plan view thereof.
The broken line showing of a fireplace in FIGS. 3 and 4, is for illustrative purposes only and forms no part of the claimed design.

FIG. 3

FIG. 4
